METHOD OF MAKING HEAT TRANSFER
TUBESStewart H. Kilmer, Ambridge, Pa., assignor to
Spang, Chalfant & Co., Inc., Pittsburgh, Pa., a
corporation of Pennsylvania

Application June 26, 1933, Serial No. 677,635

1 Claim. (Cl. 29—157.3)

My invention relates generally to the manufacture of heat-transfer tubes which comprise a tubular core upon which are shrunk a plurality of cast metal fin rings, and its principal object 5 is the provision of a new and improved heat-transfer tube which will be more desirable and will possess improved heat-transference properties.

In the present practice the cores of such heat-transfer tubes are either cold drawn or hot rolled seamless tubing. The use of cold drawn tubing has this marked advantage. Its perimetal surface is of substantially uniform diameter, and fin rings of uniform internal diameter 10 may be successfully shrunk thereon. However, the grain structure of such tubing is not refined and therefore its life in service is relatively short, owing to the extreme temperatures to which it is exposed. Experience has shown that 15 hot-rolled tubes, either as rolled or normalized, are, by reason of their superior grain structure, better than cold-drawn tubes for the class of service to which this invention relates. Probably the smoothness of the surface strains of hot-rolled tubes is greater and the stressed condition 20 of the surface of the cold-drawn tube is more susceptible to corrosion than the surface of the hot-rolled tubes.

As the tubes are subjected to changes of heat, 25 it is desirable that the tube and the rings be as nearly as possible of the same composition and structure. This will reduce the thermo-couple effects as these effects are most pronounced with couples of unlike metals. It is of the utmost importance that the fit between the tube and the 30 rings shall be uniform and intimate. This can be accomplished only by holding the diameters of the tubes and of the openings in the rings within a very close toleration limitation.

To refine the grain structure, cold-drawn tubing has to be heat-treated, but with the objectionable results that scale formation occurs and the uniformity of its perimetal surface is destroyed so that the fin rings no longer shrink 35 into close, uniform contact with the core.

In some instances, cold-drawn tubes, after heat-treatment, have been again rolled to remove the scale, but the result is a non-round 40 tube.

The result of loose or ill-fitting fin rings is an impairment of the heat-transference between the core and the fin rings as pockets are formed 45 between the core and the rings and heat-transference is by convection.

Hot-rolled seamless tubes are in more general use as cores for heat-transfer tubes because of their superior grain structure as compared with cold-drawn tubes, but the external diameter of a hot-rolled tube varies materially throughout its 5 length and it has a taper from one end to the other. The surface is rough and scaled.

Therefore, with a hot-rolled core, fin rings of different internal diameters are required to properly fit different portions of the tube. This adds 10 to the labor and expense of manufacture. If the internal diameter of the ring be too small, the ring may break in cooling, and if the broken ring be an intermediate one, a new ring must be cast in its place. On the other hand, if the ring 15 has too large an internal diameter, it may be actually loose or air pockets may be formed between the core and the ring, in either case impairing the efficiency of the heat-transference. A loose or ill-fitting ring may cause the tube to 20 burn out at that point.

My improved heat-transfer tube has a core of substantially constant external diameter and a smooth perimetal surface free from scale. As a result, the fin rings used must be of uniform internal diameter properly sized to be shrunk onto the 25 core with a close and uniform fit.

Therefore, no air pockets are formed in my tubes and no heat-transference by convection 30 takes place. Again, the rings neither become loose nor do they break upon cooling. The heat-transference is expedited and uniform throughout the entire series of rings and throughout the entire area of the individual rings.

In my improved heat-transfer tube the core is 35 formed of a length of hot-rolled seamless tubing which is finished, either by grinding or machining to produce a smooth perimetal surface of substantially uniform diameter from end to end, 40 free from scale.

I employ the proper number of fin rings having the proper uniform internal diameter so that when expanded by heating, mounted on the tube and shrunk in place, they will fit the core snugly 45 and uniformly, thus producing a durable structure having the highest heat-transference properties.

In the accompanying drawing, which is a side elevation partially in section of a heat-transfer 50 tube which embodies the principles of my invention, 1 represents the core which is a hot-rolled tube whose perimetal surface has been reduced by machining or grinding or both to produce a substantially uniform exterior diameter through- 55

out the length of the tube and a smooth, uniform surface 2, free of scale and pits.

The fin rings comprise a collar 3 and a plurality of radially extended fins 4.

5 The core is first prepared by machining and grinding the surface of the length of hot rolled tubing, the tubing being intentionally rolled oversize to allow the proper finishing operation.

10 This process permits a more accurate computation of the tolerance necessary for successfully shrinking the cast ring on the core.

15 The cast metal fin rings are machined to a uniform internal diameter so that they may be used indiscriminately in assembling them on the tube, the proper shrink interference being calculated and provided for in the machined diameters.

The rings are then heated, slipped into place on the core, and then shrunk in place.

20 The heat-transfer tubes which are the product of my improved process are superior to the present product where the fin rings are shrunk onto a hot-rolled tube without machining or grinding the tube surface, the reason for this being that

25 the machined or ground surface on which the fin rings are shrunk is in contact with the whole

area of the core of the rings which results in a uniformity of unit pressure between the two bodies and as the fin rings are shrunk on the tubing there is no chance for the scale to form between the tube and the ring as the growth of the scale comes from the tube and not the cast fin ring. The seal between the fin rings and the tubing in my heat-transfer tube made by my process furnishes a path for conducting heat from the fin ring to the tube or vice versa at a 10 very high efficiency of heat conductivity.

I claim:—

An improved process of commercially making a finned-ring heat transfer tube which comprises forming a hot rolled tube to an oversized dimension, machining said tube to a uniform diameter throughout its length thereby providing the perimetral surface free from crust, scale, pock-marks and the outer region containing stressed metal, machining the bore of cast metal fin rings 15 thereby producing uniform internal diameters, heating said rings to expand them, slipping said rings into place on said tube, and permitting them to shrink thereon in cooling.
